(57) CLAIM

I claim the ornamental design for the game controller, as shown and described.

DESCRIPTION

FIG. 1 is a top view of the game controller;

FIG. 2 is a bottom view of FIG. 1;

FIG. 3 is a left side view of FIG. 1;

FIG. 4 is a right side view of FIG. 1;

FIG. 5 is a back view of FIG. 1;

FIG. 6 is a front view of FIG. 1; and,

FIG. 7 is an alternate front view of FIG. 1, showing the directional pad element in alternate positions.

The broken lines shown are included for the purpose of illustrating portions of the game controller that form no part of the claim.

1 Claim, 7 Drawing Sheets

FIG. 2

FIG. 3

FIG. 4

FIG. 5

FIG. 6

FIG. 7
